COMBINED CAMP STOVE AND CHAIR

William A. Doppelheuer, Connellsville, Pa.

Application October 26, 1945, Serial No. 624,634

4 Claims. (Cl. 155—41)

1

This invention relates to collapsible wire grills. An object of this invention is to provide an improved grill which is formed of a collapsible frame having a heavy wire screen secured thereto, and the frame being adjusted to several positions, one of the adjusted positions of the frame being the formation of a chair.

Another object of this invention is to provide a collapsible grill having a pivoted perforate panel which, in one position thereof is adapted to overlie the top of the fuel basket, and in another position thereof is adapted to form a brace or support for the seat.

A further object of this invention is to provide a collapsible bearing for the rotatable basket or holder.

With the above objects in view, and others which may hereinafter more fully appear the invention consists of the novel construction and combination of parts, but it is to be understood that changes, variations or modifications may be resorted to which fall within the scope of the invention, as claimed.

In the drawings:

Figure 1 is a detail side elevation of a grill constructed according to an embodiment of this invention.

Figure 2 is a detail front elevation of the device.

Figure 3 is a detail plan view of the device with the swinging grate or screen in horizontal position.

Figure 4 is a detail side elevation of the device showing the manner of supporting a perforate foot holder and the optional positions of the horizontal grill member.

Figure 5 is a plan view, partly broken away, of one of the holders used with this device.

Figure 6 is a detail side elevation, partly in section, of the device when used as a chair.

Figure 7 is a plan view of another article holder.

Figure 8 is a detail end elevation of the holder shown in Figure 7.

Figure 9 is a sectional view taken on the line 9—9 of Figure 1.

Figure 10 is a sectional view taken on the line 10—10 of Figure 1.

Figure 11 is a sectional view taken on the line 11—11 of Figure 4.

Referring to the drawings the numerals 15 and 16 designate generally a pair of rectangular frames which, as shown in Figures 1 and 4, are disposed in upwardly divergent relation. The frame 15 includes a pair of parallel side bars 17, and upper and lower parallel bars 18 and 19. The frame 16 includes a pair of parallel side

bars 20 and upper and lower horizontal bars 21 and 22 connected between the side bars 20.

The side bars 17 of the frame 15 are provided with downwardly extending leg members 23 which are formed at their lower ends with horizontal feet 24. A pair of pivoted leg members 25 are pivotally mounted on pivot members 26 extending through the upper end portions of the leg members 23, and the leg members 25 are formed, at their lower ends, with feet 27.

The frame 16 has formed integral with the side members thereof flattened lower end portions 28 through which the pivot members 26 engage so that the frame member 16 will be pivotally secured to the frame structure including the frame 19, and the legs 23.

The frame 15 has mounted therein a screen 29 and the frame 16 has mounted therein a screen 30. A pair of triangularly shaped end members, generally designated as 31, are swingably carried by the frame 15, and are adapted to be coupled to the frame 16 so as to hold the two frames 15 and 16 in upwardly divergent relation. The two end members 31 are formed of a pair of downwardly convergent side members 32 and 33 which are connected together at their upper divergent ends by a horizontal connecting bar 34. The side member 33 is pivotally secured to an upright frame bar 17 by means of a pair of loops 35 which are secured to the side member 33 by welding or the like and engage about the frame member 17. The other side member 32 has secured thereto as by welding or the like a keeper or latch member 36 which is adapted to hook over the side bar 20 of the frame 16.

The end members 31 each have mounted on the upper horizontal bars 34 thereof, a holder bracket 37. The bracket 37 is constructed in the form of an elongated bar which is formed with a plurality of vertical spaced apart notches 38 opening through one edge of the bar for removably receiving the shaft 39 of a holder, such as the holder 40 shown in Figure 5, or the holder 41 shown in Figures 7 and 8.

The bracket or bar 37 is pivotally mounted between the pair of ears 42 carried by a split sleeve 43 which is fixedly secured to the bar 34 as by welding or the like, and the bracket or bar 37 is braced with respect to the bar 34 by means of a pair of downwardly extending forked or spaced apart parallel arms 44 which extend at an angle to the vertical when the bracket arm 37 is in a vertical operating position.

The legs 23 and 25 are held in downwardly divergent relation by means of a pair of pivoted

links 45 and 46 which are carried by the legs 23 and 25 and the link 46 is formed with a stop 47 engaging the lower edge of link 45, as shown in Figure 11. An auxiliary flat grill, generally designated as 48, is pivotally secured to the upper horizontal bar 21, and comprises a pair of side bars 49, and a pair of connecting bars 50 and 51. The connecting bar 51 has secured thereto a pair of loops 52 loosely engaging about the upper bar 21, so that the grill or frame structure 48 may be swung to a horizontal position over the upper ends of the frames 15 and 16, as shown in Figures 1 and 3, or may be disposed in dependent relation, as shown in full lines in Figure 4.

The frame comprising side bars 49 and the end bars 50 and 51, also includes a pair of oppositely extending feet 53 carried by the side bars 49, which, as shown in Figure 6, are adapted to engage on extensions 45a of links 45.

To dispose the grill 48 in the position shown in Figure 6, the side frame 16 is disengaged and lowered from the end members 31, and forms a seat which, as illustrated, has as a back the stationary frame 15. The grill 48 also includes a wire mesh 54 disposed between the side and end bars.

Referring now to Figure 5 there is disclosed one form of holder which is of cylindrical construction, and which includes a cylindrical side wall 55, and end walls 56 and 57. The oppositely extending shaft 39 extends from the end walls 56 and 57. The holder 40 also includes a closure 58, which may be locked in closed position by means of hooks 59 secured to the closure 58, and engageable with eyes 60 which are welded or otherwise secured to the side wall 55 of the holder.

In Figures 7 and 8 there is disclosed a rectangular holder which includes a box-like body 61 formed with a reinforcing rim 62 and the holder 41 includes oppositely extending shaft 63 carried by plates 64 which are secured to the end walls of the body 61. The body 61 has pivotally secured thereto, a perforate closure 65 which is pivotally secured at one end to links 56 fixed to the reinforcing rim 62 and a pair of hooks 66 are carried by the closure 65 and engage eyes 67 which are fixed to one of the end walls of the body 61.

In the use and operation of this device where a steak or other article is to be cooked by fuel, such as charcoal or the like which is disposed in the basket formed by the frame members 15 and 16 and the end members 31, the grill 48 is swung upwardly to a horizontal position such as the position shown in Figures 1 and 3.

Where a chicken or other article is to be cooked the cylindrical grill member or holder 40 may be inserted in selected notches 38 of the bracket members 37, which, at this time, are in a vertical position. The holder 40 may then be rotated until the article is cooked.

Where a flat article of food is to be cooked the flat holder 41 may be substituted for the cylindrical holder 40.

If it is desired to use the device as a chair the flat grill 48 is swung downwardly and the end members 31 are released from the frame 16 so as to permit this frame to be lowered to the position shown in Figure 6. At this time the grill 48 engages the extensions 45a and the end members 31 may, if desired, be swung outwardly.

I claim:

1. A collapsible grill comprising a pair of rectangular frames, a pair of legs fixedly carried by one of said frames, a second pair of legs pivotally carried by said one frame, means pivotally securing the other frame to said one frame, a screen in each of said frames, a pair of triangular end frames, means pivotally securing said end frames to said one frame, releasable latching means for latching said end frames to said other frame, a triangular screen in each end frame, a notched holder supporting bar for each end frame, means pivotally mounting each bar on its corresponding end frame, and a forked supporting member carried by each bar engaging said corresponding end frame for holding said bar upright.
2. The device, as set forth in claim 1, including a flat grill member carried by said other frame and swingable to a position overlying said pair of frames.
3. The device, as set forth in claim 1, including a flat grill member pivotally carried by said other frame and swingable to a position overlying said pair of frames, said flat grill member also including a pair of outwardly and oppositely directed feet, and means carried by said first pair of legs for engagement by said feet for holding said other frame when the other frame is swung down to horizontal seat forming position and the grill member is swung to extend downwardly and rearwardly.
4. A convertible grill and chair comprising a pair of rectangular frames pivotally connected together at one end in upwardly divergent relation, a pair of legs fixedly carried by one of said frames, a second pair of legs pivotally carried by said one frame, a pair of triangular end frames, means pivotally securing said end frames to said one frame, releasable latching means for latching said end frames to said other frame, a mesh covering on said frames, a grill member pivotally carried by the free end of the other of said frames, pivoted links between said pairs of legs, certain of said links extending beyond the leg to which they are connected forming supporting extensions in the extended position of said extensions, said grill member being adapted in one position to overlie the divergent ends of said frame members, and to be swung to extend downwardly to engage said extensions to hold said other frame in downwardly swung horizontal seat forming position.

WILLIAM A. DOPPELHEUER.
